(57) **CLAIM**

The ornamental design for a broom and dustpan set, as shown and described.

DESCRIPTION

FIG. 1 is a top, front, right perspective view showing my new design of a broom and dustpan set;

FIG. 2 is a rear, left elevation view thereof;

FIG. 3 is a top, front, right perspective view showing the broom and dustpan set in separate state;

FIG. 4 is a front elevation view of the broom and dustpan set of FIG. 1;

FIG. 5 is a rear elevation view thereof;

FIG. 6 is a left side view elevation thereof;

FIG. 7 is a right side view elevation thereof;

FIG. 8 is a top plan view thereof; and,

FIG. 9 is a bottom plan view thereof.

The broken lines in the drawings illustrate features of the broom and dustpan set that form no part of the claimed design.
